UNITED STATES PATENT OFFICE.

NELS P. WALTERS, OF FORT MADISON, IOWA.

RAIL-JOINT.

No. 830,754.

Specification of Letters Patent.

Patented Sept. 11, 1906.

Application filed February 23, 1906. Serial No. 302,552.

To all whom it may concern:

Be it known that I, NELS P. WALTERS, a citizen of the United States, residing at Fort Madison, in the county of Lee and State of Iowa, have invented a new and useful Rail-Joint, of which the following is a specification.

This invention relates to rail-joints; and its object is to produce means whereby the abutting ends of rails are prevented from sagging one below the other so as to cause pounding by car-wheels passing over the joints.

A still further object is to provide supporting means which will not interfere with the expansion or the contraction of the rails and which is adapted to be used in connection with fish-plates of the usual construction.

With the above and other objects in view the invention consists of a block or key adapted to be inserted in the registering recesses in the ends of two abutting rails so as to hold said ends against independent vertical movement. The key has forked ends adapted to embrace the webs of the rails, so as to prevent lateral displacement of the key. The sides of the key are preferably rounded, so as to fit snugly within the inner faces of the fish-plates.

The invention also consists of certain other novel features of construction and combinations of parts, which will be hereinafter more fully described, and pointed out in the claims.

In the accompanying drawings are shown the preferred forms of the invention.

In said drawings, Figure 1 is a side elevation of the rail-joint with the fish-plate removed. Fig. 2 is a horizontal section through the joint. Fig. 3 is a transverse section therethrough. Fig. 4 is a detail view of the key, and Fig. 5 is a similar view of a modified form of key.

Referring to the figures by numerals of reference, 1 1 are rails having rectangular recesses 2 in the ends of the webs thereof, said recesses being of less width than the height of the webs, so that a considerable portion of the web remains between each recess and the head of the rail.

When two rails are placed together with their ends in contact, the recesses therein will register, and these recesses are adapted to receive a supporting-key 3, which is equal in length to the combined lengths of the two recesses in which it is located. Extending from the ends of the key are parallel arms 4, forming forks adapted to embrace the webs

and hold the key against displacement. The side faces of the key and arms are rounded, so as to fit within the concavities formed within the inner faces of the ordinary fish-plates 5. 6c These fish-plates are adapted to be bolted to the rails in the usual manner and will spring inward at their ends to a certain extent, thereby acting as nut-locks, because they will bind upon the nuts 6 upon the bolts 7 65 and prevent them from being unscrewed unless subjected to more than the ordinary pressure. While the key herein described is especially adapted for use in connection with rails having beveled overlapping ends, it can 70 also be employed with rails having the ordinary square ends. Moreover, instead of forking the ends of the key the arms 4 may be dispensed with, as shown at 8. With this construction, however, the key is liable to 75 fall out of position while the fish-plates are being secured and therefore the key utilizing arms 4 will be found more desirable. As the recesses are not disposed close to the heads of the rails there is no danger of the rail breaking 80 when subjected to extreme downward pressure, but instead the key will break and leave the rail uninjured.

What is claimed is—

1. In a rail-joint the combination with 85 abutting rails having registering recesses in the ends of their webs; of a substantially rectangular key seated within the recesses and having rounded exposed faces, and fish-plates bolted upon the webs and embracing 90 said rounded faces.

2. In a rail-joint, the combination with abutting rails having registering recesses in the webs thereof; of a substantially rectangular key seated within the recesses and having 95 forked ends embracing the webs, the exposed faces of the key being rounded.

3. In a rail-joint, the combination with abutting rails having registering recesses in the webs thereof; of a substantially rectangular key seated within the recesses and having forked ends embracing the webs, the exposed faces being rounded, and fish-plates screwed 100 upon opposite faces of the webs and embracing the rounded faces of the key.

In testimony that I claim the foregoing as my own I have hereto affixed my signature in the presence of two witnesses.

NELS P. WALTERS.
